FREDRICK MENZER, OF SAN FRANCISCO, CALIFORNIA.

Letters Patent No. 99,455, dated February 1, 1870.

IMPROVED EXTENSION-BEDSTEAD.

The Schedule referred to in these Letters Patent and making part of the same

To all whom it may concern:

Be it known that I, FREDRICK MENZER, of the city and county of San Francisco, State of California, have invented an Improved Extension-Bedstead; and I do hereby declare the following description and accompanying drawings are sufficient to enable any person skilled in the art or science to which it most nearly appertains, to make and use my said invention or improvements, without further invention or experiment.

My invention relates to an improvement in bedsteads and cribs; and

It consists in a new arrangement of the parts, so that it may be folded into a small compass, and form a single bed or crib, or, when desired, can be extended in its several parts, so as to form a double bed or crib, for the accommodation of more than one occupant.

In order to more fully illustrate and explain my invention, reference is had to the accompanying drawings, forming a part of this specification, in which—

A represents the head-board, and B, the foot-board of a bed or crib.

In my bedstead, these parts are made of the width of those employed in single beds, and have a second or supplemental head and foot-board, A' B', hinged to them on one side, so that they can be folded back to back with the boards A and B, and thus form a head and foot-board of double the ordinary thickness, and are secured in this position by hooks and staples b.

Instead of the slats usually employed, I form the bed-bottom of a series of frame-work, so constructed that they can be extended to the desired width, to form a bottom for an extended bed.

The boards d are secured to the stationary head and foot-board, at the height which it is desired to have the bed-bottom. The inner edges of these boards are grooved.

A frame-work, C, whose end-strips are provided with tongues which slide in the grooves in the boards B, is then placed between them.

A second frame-work, D, having its outer strips tongued, is then placed inside the frame-work C, and moves in grooves in the frame C.

This frame D is secured at one side to the side rail E of the bed, which is independent of the head and foot-board, and which, when drawn out or extended, also carries with it the frames forming the bottom, which, when extended to the proper position, are stopped by blocks e.

The swinging head and foot-boards A' and B' are then unhooked, and swung around until they stand in a line with the stationary head and foot-boards A and B, where they are secured by hooks and staples, or other equivalent device.

The mattress F is made so that it can be folded together, and form a mattress for a single bed, or opened out to fit the extended bed, as desired, by either constructing it in two parts, and uniting them together loosely, or by constructing it in one piece, and leaving a folding-crease through its middle.

A bedstead or children's crib constructed in this manner can be extended at night, so as to accommodate more than one person, and in the morning folded up, so as to occupy but half the original space, while the appearance of the bedstead will be that of a single bed. The cost of construction will be but little more, if any, than that of an ordinary bedstead.

Having thus described my invention,

What I claim, and desire to secure by Letters Patent, is—

A bedstead, in which a sliding extension of the bottom is combined with hinged and folding ends, so as be capable of forming a complete bedstead, of double or increased width, constructed as above described.

In witness whereof, I have hereunto set my hand and seal.

FREDRICK MENZER. [L. S.]
